UNITED STATES PATENT OFFICE.

EPHRAIM HAMBUJER, OF DETROIT, MICHIGAN, ASSIGNOR OF ONE-HALF TO
D. P. FRANK AND JOHN KOCH, BOTH OF SAME PLACE.

BUTTON-HOLE STAY FOR BOOTS AND SHOES.

SPECIFICATION forming part of Letters Patent No. 288,794, dated November 20, 1883.

Application filed August 27, 1883. (No model.)

To all whom it may concern:

Be it known that I, EPHRAIM HAMBUJER, of Detroit, in the county of Wayne and State of Michigan, have invented new and useful

5 Improvements in Button-Hole Stays for Boots and Shoes; and I do hereby declare that the following is a full, clear, and exact description thereof, reference being had to the accompanying drawing, which forms a part of this

10 specification.

The nature of this invention relates to certain new and useful improvements in the manufacture of what are commonly denominated "buttoned" boots or shoes, and other articles 15 wherein button-holes are liable to be torn out.

The invention consists in securing between the outer portion of the article and the lining thereof corrugated annealed wire, secured in such manner that one of the corrugations of 20 the wire lies in front of the button-hole, to enable it to withstand the strain, the next corrugation in the opposite direction lying between two adjacent button-holes, as more fully hereinafter described.

25 In the accompanying drawing, which forms a part of this specification, my invention is shown as applied to the front flap of a lady's buttoned shoe, in which A represents a series of button-holes, and B (shown in dotted lines) 30 represents the corrugated annealed wire secured between the front and the lining of the article, so that one of the corrugations is in front of and in close proximity to the outer end of the button-holes, the next corrugation

pointing to the rear between such button-holes, 35 so that the connecting portions between the front and rear corrugations lie alongside of the button-holes.

The wire may be very small, so much so as not to make the article appear badly, and is 40 secured between the fly and the lining by gumming, so as to give under the strain of the button-hook, while the flap is sufficiently elastic to resume its original position when the strain is removed.

45 I am aware that it is not new to run a comparatively straight wire along and parallel to the edge of the button-hole flap, between said edge and the button-holes; but such a wire would be very stiff, and would be troublesome 50 in bending the foot in walking, whereas my wire, being curved and running back parallel with the sides of the button-holes, will be very flexible, and thus overcome this difficulty, and at the same time help to strengthen the button-holes on the sides as well as in front.

55 What I claim as my invention is—

As a means of staying button-holes in boots and shoes, a corrugated wire arranged so as to extend up one side, along the front of and 60 down the other side of each button-hole, and secured between the front and the lining by gumming, substantially as described.

E. HAMBUJER.
